UNITED STATES PATENT OFFICE.

NICHOLAS S. VEDDER, OF TROY, AND TOBIAS S. HEISTER, OF LANSINGBURG,
ASSIGNORS TO NICHOLAS S. VEDDER, OF TROY, NEW YORK.

DESIGN FOR A COOKING-STOVE.

Specification forming part of Design No. 6,307, dated December 17, 1872.

To all whom it may concern:

Be it known that we, NICHOLAS S. VEDDER, of the city of Troy, in the county of Rensselaer and State of New York, and TOBIAS S. HEISTER, of Lansingburg, in said county and State, have jointly invented and produced a new and original Design for Cook-Stoves, of which the following is a specification, reference being had to the accompanying wood cut or engraving of a stove which embodies our said design.

One part of our invention consists of the compound ornament Z, shaped and arranged on a door or panel of a stove, substantially as shown in the aforesaid wood-cut. Another part consists of the ornament A, shaped and arranged on a door or doors or panel or panels of a stove, substantially as shown in the aforesaid engraving. Another part consists of the particular ornamental beading B, arranged along a border-molding of a panel on

a door or plate of a stove, substantially as shown in the engraving. Another part consists of the combination of the ornamental beading B with a plain panel, C, and the ornament Z or A, as shown in the wood-cut.

What we claim as our invention is—

1. The ornament Z, shaped and arranged as above described.
2. The ornament A, shaped and arranged as above set forth.
3. The ornamental beading B, shaped and arranged along the border-molding of a panel, as herein set forth.
4. The design for the combination of the beading B, panel C, and ornament Z or A, as herein set forth.

NICHOLAS S. VEDDER.
TOBIAS S. HEISTER.
